US00D945613S

(12) **United States Design Patent** (10) Patent No.: **US D945,613 S**
(45) Date of Patent: **** Mar. 8, 2022**

(54) **HANDLE FOR MEDICAL INSTRUMENTS**

(71) Applicant: **KARL STORZ SE & Co. KG**,
Tuttlingen (DE)

(72) Inventors: **Judith Holzer**, Tuttlingen (DE); **Daniel
Notheis**, Tuttlingen (DE)

(73) Assignee: **KARL STORZ SE & CO. KG**,
Tuttlingen (DE)

(**) Term: **15 Years**

(21) Appl. No.: **29/744,627**

(22) Filed: **Jul. 30, 2020**

(30) **Foreign Application Priority Data**

Jan. 31, 2020 (EM) 007574835

(51) LOC (13) Cl. **24-02**

(US) LLP

CLAIM

The ornamental design for a handle for medical instruments, as shown and described.

DESCRIPTION

FIG. 1 is a perspective view of a handle for medical instruments showing our new design;

FIG. 2 is a front view thereof;

FIG. 3 is a rear view thereof;

FIG. 4 is a left side view thereof;

FIG. 5 is a right view thereof;

FIG. 6 is a top view thereof; and,

FIG. 7 is a bottom view thereof.
